William H. Hales
Stlly.

UNITED STATES PATENT OFFICE.

JOHN THOS. MCGRATH, OF BLOOMINGTON, ILLINOIS.

OIL BURNER.

Application filed April 24, 1919. Serial No. 292,295.

To all whom it may concern:

Be it known that I, JOHN T. MCGRATH, a citizen of the United States, and a resident of Bloomington, in the county of McLean 5 and State of Illinois, have invented certain new and useful Improvements in Oil Burners; and I do hereby declare that the following is a full, clear, and exact description thereof, reference being had to the accompanying drawings, and to the characters of reference marked thereon, which form a part of this specification.

This invention relates to improvements in oil burners adapted to be used in connection with fuel oil furnaces for any desired purpose and to which the fuel oil and air are fed under pressure and are intermixed under pressure to produce an atomized fuel constituent which, at the furnace, 20 is delivered into a large volume of low pressure air to carry the mixture generated to the point of application of the heat.

Among the objects of the invention is to provide improved means for mixing air with the fuel oil so constructed and arranged that the supply means can be very delicately adjusted to accurately obtain a properly proportioned mixture.

A further object of the invention is to provide an improved auxiliary air inlet to admit an auxiliary supply of free air to the burner which is adapted to be mixed with the pressure oil and air at the immediate point of mixture of the latter and in a manner to obtain a uniform desired mixture.

A further object of the invention is to provide a novel construction of the burner head to bring the air and oil together and to agitate the oil at the point where the air 40 first contacts with it so as to produce better atomization.

Another object of the invention is to provide, in combination with the air and fuel mixing elements of a high pressure burner, 45 means for admitting at the furnace the burning mixture along with a large volume of low pressure air as furnished by a fan blast, so arranged relatively to the high pressure mixture outlet as to gently bring 50 the full heat of the flame on the material being heated in a manner to slowly saturate the material with heat and to avoid burning the material.

Other objects of the invention are to generally simplify and improve oil burners, and

the invention consists in the combination and arrangement of the parts shown in the drawings and described in the specification, and is pointed out in the appended claims.

In said drawings,

Figure 1 is a vertical section of an oil burner embodying my invention.

Figure 2 is a rear end view of the burner head.

Figure 3 is a transverse section on the line 65 3—3 of Figure 1.

Figure 4 is a perspective detail showing the adjustment for the furnace air inlet valve.

Figure 5 is a detail on line 5—5 of Fig. 70 2.

As shown in the drawings, 10 designates an elbow shaped casing or conduit, comprising a horizontal outlet member 11 which is adapted to extend into the furnace and a 75 downwardly extending receiving member 12 adapted to be connected to a blast fan to furnish air in volume at a low pressure through the conduit to the furnace. The flow of air through the casing is controlled 80 by a butterfly valve 13, the operating handle 14 of which is engaged by stops 15 and 16 to arrest the valve in its open or closed position. Said valve 13 is adapted to be locked in adjusted positions between its limits of 85 movement by the spring pressed pawl 14' shown in Figure 4 carried by the valve shaft to engage stop openings 12' in wall of inlet 12. Said valved elbow casing constitutes an air inlet conduit of large cubical 90 contents adapted to controllably conduct air in a large volume and at relatively low pressure to the furnace, to be intermixed with the flame of the high pressure burner, so as to distribute the flame to and cause it 95 to softly impinge on the material being heated. The said inlet is, therefore, a volume, low pressure, air inlet.

17 designates a mixing tube or chamber which extends axially through the outlet member of the volume, low pressure casing. It is made of considerably smaller diameter than the outlet or discharge orifice of the low pressure conduit and is designed to discharge burning mixture under high pressure 100 through the core of the relatively low pressure, large volume of air delivered through the conduit outlet or discharge orifice. Said tube is seated in a thickened hollow portion 105 18 of said casing at the exterior angle of 110

the junction of the members thereof and is held in place by a set screw 19. Made integral with said tube 17 or fixed thereto in any suitable manner is, what may be 5 termed, a feed head designated as a whole by 20. Said head is provided with a branch or connection 21 interiorly threaded to receive a liquid fuel pipe adapted to deliver fuel under pressure to said head. The head 10 is provided inside said connection with a liquid fuel receiving chamber 22 which is formed in a transverse, cored out member 23 of the head. The said chamber 22 terminates at its upper end in a seat 24, shown 15 herein as a conical seat, which is engaged by a valve 25 that is held on the seat by a spring 26, whose pressure is adapted to be regulated by an adjusting screw 27 that is threaded in the head and extends into a 20 chamber 23' in the member 23 in which said spring is contained. 28 designates an open port leading from the chamber 23' just above the valve seat to a mixing chamber 29 that is in open communication with the receiving end of the mixing tube. 25

The head is formed in rear of the member 23 with an air inlet chamber 30 to receive air, and said chamber is in open communication with the mixing chamber 29 through 30 passages 30' around the sides of the member 23. The head is also provided at its rear end with a threaded intake 32 adapted for connection to a pipe leading from a source of air and/or steam under pressure. Said 35 intake 32 is in open communication with the inlet chamber 30.

33 designates an auxiliary air inlet that is adapted to receive free air, as atmospheric air, and deliver it to the chamber 30. Said 40 inlet 33 may be controlled by any suitable type of valve that can be adjusted to deliver any desired volume of free air through the inlet 33 to the receiving chamber 30. As 45 shown, a butterfly valve 34 is employed, the shaft 35 of which is mounted to rock in the walls of the inlet, and is provided with an operating lever 36. Any suitable means may be employed for locking the valve 34 in adjusted positions. For instance, I may employ a locking plate or flange 37 fixed to the 50 head and provided with a plurality of openings to receive a locking pin 38 which is adapted to extend through an opening in the handle 36 of said butterfly valve.

55 The said liquid fuel valve 25 is herein shown as formed on a stem 39 which extends through the fuel inlet chamber 22 in the direction of the inlet connection 21. Said stem is tapered towards its free end and is spirally fluted or otherwise formed to cause the liquid fuel passing thereover under pressure to be given a swirling motion, and to thereby improve the mixing of the liquid fuel and air after the fuel has been discharged through 60 the port 28 into the fuel constituent mixing

chamber. The valve and its stem, as herein shown, have the form of an ordinary wood screw.

Extending across the burner tube 17 near its discharge end is a spreader 40 of any suitable construction to cause the atomized fuel mixture to be spread at the point of leaving the burner tube so as to strike the tapered side walls of the combustion chamber in the furnace. 75

In operation, the valves connected to the air inlet and fuel inlet pipes are opened to admit liquid fuel and air under pressure to the respective chambers 22 and 30. The strength of the spring 26 is such as to operate against varying liquid fuel pressures to deliver the desired quantity of fuel to the head; it being understood that the adjustment is such that the fuel pressure will overcome the strength of the spring to permit delivery of a desired amount of fuel to the chamber 29 through the port 28. Air under pressure passes to the mixing chamber around the member 23 and is mixed with the fuel at a time when the fuel is swirling, due 80 to its passage over the spiral convolutions of the valve stem. This mixture is delivered through the mixing tube 17 against the spreader 40 and into the furnace and is there mixed with and directed by the large body 85 of low pressure air that is taken through the casing 10, the air valve 13 of which is adjustably open to admit a desired volume of air. 90

The auxiliary valve 34 furnishes means 100 whereby air may be proportioned to the atomized mixture more closely than such proportion can be afforded by adjusting the intakes of air and fuel under pressure. The said valve 34 is provided with means for 105 adjusting it through small increments of movement and the air is delivered through the inlet 33 by the force of air under pressure passing through the chamber 30 by way of inlet 32. It has been found in practice that 110 the use of the auxiliary valve located and operating as shown very substantially refines the operation of the burner, in that it clarifies the flame and gives perfect combustion and various ranges of temperature. 115

The location of the inlet 33 as shown in the drawings is of considerable advantage in respect to the unhindered delivery of the free air to the chamber 30 as well also as producing a symmetrical structure. 120

Another feature of advantage lies in the construction and the location of the fuel swirling means at such point that the air is brought at once into contact with the swirling fuel so that better conditions are provided for intermixing the fuel and air. 125

By reason of the large diameter of the nozzle or discharge orifice end of the conduit 11, relatively to the nozzle area of the elongated combustion chamber 17, the burning mix- 130

ture under pressure from the latter can be freely discharged into the core of the large volume of low pressure air moving through the conduit 11, into the furnace, and thereby enable the combined mixture to be gently impinged on the material being heated and avoiding local overheating of said material which would occur if the material were attacked by the burning mixture under pressure from the tube 17. The valves 13, 34 and the liquid fuel and pressure air valves can be readily adjusted to produce the most exact effects at the heating zone in the furnace; and the free egress from the large diameter conduit 11 permits unobstructed flow of the air and burning mixture into the furnace, without restraint except as afforded by the control valves.

I claim as my invention:

1. A liquid fuel burner comprising a low pressure air inlet conduit adapted to discharge air in large volume and at low pressure into a furnace, with means to control the air flow therethrough, and a high pressure mixing chamber in rear of and adapted to discharge its mixture under pressure into the furnace through an elongated combustion tube whose nozzle is disposed in the core of the low pressure air discharged from said conduit, said high pressure mixing chamber having separate adjustable means to supply liquid fuel and air under pressure to said chamber and to mix them therein and to discharge the burning mixture into said tube.

2. A liquid fuel burner comprising a low pressure air inlet conduit adapted to discharge air in large volume and at low pressure into a furnace, with means to control the air flow therethrough, a high pressure mixing chamber in rear of and adapted to discharge its mixture under pressure into the furnace through an elongated combustion tube whose nozzle is disposed in the core of the low pressure air discharged from said conduit, said mixing chamber having separate adjustable means to supply liquid fuel and air under pressure to said chamber and to mix them therein, and means to supply air at atmospheric pressure to said high pressure mixing chamber.

3. A liquid fuel burner comprising a low pressure air inlet conduit adapted to discharge air at low pressure and in large volume into a furnace and provided with a regulating valve, a combustion tube having its orifice discharging into the air as it issues from said conduit, a mixing chamber adapted to discharge its mixture through said combustion tube, and separate means to supply liquid fuel and air under pressure to said chamber and mix them therein for combustion and for discharge through said tube, and nozzles of said latter tube and of said conduit being coaxial and of such relative

discharge areas as to subdue the burning mixture issuing from the combustion tube to cause the high and low pressure constituents to impinge softly on the material being heated.

4. A liquid fuel burner comprising a low pressure air inlet conduit having an enlarged free discharge nozzle adapted to discharge into a furnace, and a high pressure mixing chamber having communication at one end with an elongated combustion tube, said tube having at its other end a discharge nozzle arranged axially in the discharge end of said conduit and adapted to discharge its burning mixture under high pressure into the furnace through the core of the low pressure air issuing in large volume from said conduit to the furnace, separate means to supply liquid fuel and air under pressure to said chamber and to mix them therein for discharge into and through the combustion tube, means to supply air at atmospheric pressure to said high pressure mixing chamber, and a controlling valve in said low pressure air inlet conduit.

5. A liquid fuel burner comprising a low pressure air inlet conduit having an enlarged free discharge nozzle adapted to discharge air in large volume and under low pressure into a furnace and provided with a controlling valve, a combustion tube, extending axially through said conduit and having a discharge orifice restricted relatively to and axially in the outlet of said conduit, a high pressure mixing chamber connected to the rear end of said combustion tube, separate means to adjustably supply liquid fuel and air under pressure to said mixing chamber and to mix them therein, and an adjustable free air inlet opening at the rear of said mixing chamber.

6. A liquid fuel burner comprising a low pressure air inlet conduit of elbow shape, one member of which terminates in an enlarged unrestricted discharge nozzle adapted to discharge into a furnace, a controlling valve in the other member of said conduit, a combustion tube extending through said first mentioned member, a high pressure mixing chamber connected to the rear end of said combustion tube and provided with means separately and adjustably to permit the supply of liquid fuel and air under pressure to said chamber and to mix them therein, and means to admit free air to said mixing chamber, the nozzle of said combustion tube discharging coaxially with the outlet of said low pressure air inlet conduit, and constituting the only outlet from said high pressure burner.

7. In a liquid fuel burner, the combination with an elongated mixing tube and its head at the rear end of said tube, of separate means for supplying liquid fuel and air under their own initial pressures to said head,

- 4
- constructed with means to mix the fuel elements under pressure in said head, said head being provided in rear of the point of mixture of the air and fuel under pressure with 5 an inlet open to the atmosphere, separate from the said air supply under pressure, and an adjusting valve in said inlet.
8. In a liquid fuel burner, a head, separate means for supplying liquid fuel and 10 air under their own initial pressures to the head, constructed with means to mix the fuel elements in the head, and auxiliary means separate from the pressure supply means to supply free air to the head for admixture with said fuel elements in the head.
9. In a liquid fuel burner, a head formed 15 to provide an air inlet chamber, a liquid fuel inlet chamber, and a mixing chamber, a connection to deliver air under pressure to the air inlet chamber, a connection to deliver liquid fuel under pressure to the fuel inlet chamber, and a valve between said liquid fuel chamber and the mixing chamber, spring held against and adapted to be 20 opened by the pressure of the liquid fuel.
10. In a liquid fuel burner, the combination with a burner tube and a head formed 25 to provide an air inlet chamber, a liquid fuel inlet chamber, and a mixing chamber, the latter in communication with said tube, a connection to deliver air under pressure to the air inlet chamber, a connection to deliver liquid fuel under pressure to the fuel inlet chamber, and a valve between said liquid 30 fuel chamber and the mixing chamber, spring held against and adapted to be opened by the pressure of the liquid fuel.
11. In a liquid fuel burner, a head formed 35 to provide an air inlet chamber, a liquid fuel inlet chamber, and a mixing chamber, a connection to deliver air under pressure to the fuel inlet chamber, a valve between said liquid fuel inlet chamber and the mixing chamber, spring held against and adapted to be 40 opened by the pressure of the liquid fuel, and means to regulably supply free air to said air inlet chamber.
12. In a liquid fuel burner, a head formed 45 to provide an air inlet chamber, a liquid fuel inlet chamber, and a mixing chamber, a connection to deliver air under pressure to the air inlet chamber, a connection to deliver liquid fuel under pressure to the fuel inlet chamber, a valve between said liquid fuel inlet chamber and the mixing chamber, spring held against and adapted to be 50 opened by the pressure of the liquid fuel, a port opening to said air inlet chamber, and open to atmosphere, and a regulating valve 55 in said port.
13. A liquid fuel burner comprising a casing having a member adapted to be inserted through the furnace wall, and an angularly disposed member adapted for connection with an air supply, a valve to control 60 the flow of air through said casing, a burner tube extending through the outlet chamber of the casing, a head connected to said tube, separate means for supplying liquid fuel and air under pressure to the head, constructed with means to mix the fuel elements in the head and deliver the mixture to said tube, and auxiliary means to regulably supply free air to the head for admixture with 65 said fuel elements.
14. In a liquid fuel burner, a head formed to provide an air inlet chamber, a mixing chamber, and a liquid fuel inlet chamber provided therebetween and the mixing chamber with a valve seat, a valve, spring held against the seat, and provided with a spirally fluted stem extending towards the receiving end of said chamber, a connection to deliver air under pressure to the air inlet chamber, and a connection to deliver liquid 70 fuel under pressure to the fuel inlet chamber.
15. In a liquid fuel burner, a head formed to provide an air inlet chamber, a mixing chamber, and a liquid fuel inlet chamber provided therebetween and the mixing chamber with a valve seat, a valve, spring held against the seat, and provided with a spirally fluted stem extending towards the receiving end of said chamber, means to 75 vary the force of the spring acting against said valve, a connection to deliver air under pressure to the air inlet chamber, and a connection to deliver liquid fuel under pressure to the fuel inlet chamber.
16. In a liquid fuel burner, a head formed to provide an air inlet chamber, a mixing chamber, and a liquid fuel inlet chamber provided therebetween and the mixing chamber with a valve seat, a valve, spring held against the seat, and provided with a spirally fluted stem extending towards the receiving end of said chamber, a connection to deliver air under pressure to the air inlet chamber, a connection to deliver liquid fuel under pressure to the fuel inlet chamber, and auxiliary means to regulably supply free air to the head for admixture with the fuel elements delivered under pressure to 80 the head.
- In witness whereof I claim the foregoing as my invention, I hereunto append my signature at Bloomington, Illinois, this 18 day of April, 1919.
- JOHN THOS. McGRATH.
